UNITED STATES PATENT OFFICE.

GEORGE HERBERT BENTLEY AND EDMUND GARDNER APPLEBY, OF LONDON,
ENGLAND.

GAS PRODUCER.

Application filed March 13, 1923. Serial No. 624,816.

To all whom it may concern:

Be it known that we, GEORGE HERBERT BENTLEY and EDMUND GARDNER APPLEBY, both subjects of the King of Great Britain, residing at London, England, have invented new and useful Improvements in Gas Producers, of which the following is a specification.

This invention relates to gas producers, 10 retorts and the like, used in the production of gas, and the objects of the invention are:—

(1) The provision of means for evenly agitating the upper portion of the ash bed 15 and lower portion of the incandescent fuel bed.

(2) The distribution of the blast of air or air and steam evenly in the top of the ash bed.

(3) The reduction of the cost of a gas producer or retort by the reduction in size of the ash pan, and in the case of a producer by the elimination of the revolving grate usually employed.

The gas producer comprises a shell preferably circular in cross section to which fuel is supplied at the top and is maintained in a state of incandescence by a blast of air or air and steam. The shell may be carried by columns and has beneath it a rotating ash pan supported on rollers or balls.

According to this invention a blast tube passes centrally through, is secured to and rotates with the ash pan. The tube has mounted upon its upper end arms at such a height that the upper surfaces of the arms extend to the top of the ash bed, that is, to slightly below the hollow shell. The arms are preferably triangular pyramids or plough-shaped and are hollow and are provided with outlets. To the end of the arms is preferably secured a hollow ring which preferably extends beneath and is protected from excessive wear and heating by the wall 35 of the casing. The ring is provided with perforations in its bottom or rear walls or in both. An air supply is connected to the blast tube, the air passing through the tube to the arms and the ring and issuing from the perforations in them escapes to the fuel in the casing at points in the upper level 40 of the ash bed whereby the air does not pass through the bulk of the ash bed as is usual and is moreover supplied to that part of

the fuel which has just been agitated by the 55 arms.

The arms may be provided with upwardly extending lugs for agitating the fuel preferably so situated relatively to the perforations in the rear surfaces of the arms as to 60 be in advance of them when the arms are rotated. The arms agitate the fuel at the top of the ash bed and their formation causes the ash to be pressed down in the ash pan from which it is removed by a scraper 65 of ordinary construction.

Steam to be added to the air supply is obtained from water which has been heated either in the jacket of the producer or of the agitator or poker, and the hot water or 70 steam is led to a spraying apparatus in the blast tube passing through the ash pan. The tube arms being highly heated by the ashes surrounding them causes steam to be formed which passes with the air blast to the fuel. 75

In some cases no water seal is provided and it is therefore unnecessary to provide the ash pan with sides, the ash pan being confined in an air or gas-tight casing.

The annexed drawings show apparatus for 80 use in the production of gas made in accordance with this invention.

Figure 1 is a vertical section of a gas producer having a water seal, Figure 2 is a plan view of the rotary arms and ring, Figure 3 is a vertical section of one of the arms, Figure 4 is a vertical section of a gas producer having no water seal, Figure 5 is a plan view of the rotary arms and ring, Figure 6 is a horizontal section of the ash pan and 90 Figure 7 is a vertical section of a modification of the producer shown in Figure 4 illustrating means for supplying water to the blast.

In all the figures 10 is a shell to the top 95 of which fuel is supplied and 11 is an air main through which air is supplied to a blast tube 12 having at its upper end arms 13 which extend to the top of the ash bed slightly below the shell 10. To the ends of the arms 13 is secured a hollow ring 14 which extends beneath and is protected by the wall of the shell 10. Steam may be supplied through a pipe 111 opening into the air supply pipe 11 and provided with a valve 100 if desired.

In Figures 1 to 3 the arms 13 have holes 131 on their rear surface to allow of the es-

- cape of air and steam to the fuel. The hollow ring 14 is supplied with air and steam from the arms 13 and has holes 141 in its inner wall and holes 142 in its bottom wall both groups of holes being for the exit of air and steam. On the upper surface of the arms 13 also are lugs 133 so situated relatively to the holes 131 as to be in advance of them when the arms are rotated. Below 10 the shell 10 is fixed a skirt 15 which extends into an ash pan 16 fixed to and rotating with the blast tube 12 and supported by rollers 17. The ashes are pressed down into the ash pan 16 by the plough-shaped arms 13 and 15 are removed from the ash pan by a scraper 18.

- In Figures 4 to 6 the arms 13 are provided with holes 131 for the exit of air and steam whilst the ring 14 is of oval section 20 and is provided with holes 141 in its inner wall. In this case the end of the shell 10 is fitted with a casing 19 through which the blast tube 12 passes and to the tube is fixed a plate 20 constituting a rotating ash pan. 25 The ashes are removed by a pivoted scraper 21 and directed into a chute 22.

- In the modification shown in Figure 7 the shell 10 has a water jacket 101 from which a pipe 102 leads to another pipe 23 and in 30 the shell 10 are rotating pokers 24 similar to those disclosed in our Patent 1,391,236, of Sept. 20, 1921, which are water jacketed, the jacket being connected to the pipe 23 by a pipe 231. The pipe 23 leads the water 35 or steam into the blast tube 12 and has at its end a sprayer 25 by which the heated water or steam from the water jacket is sprayed into the blast passing to the arms 13.

- In Figures 1 to 3 the blast tube 12 is rotated by means of a toothed ring 121 on the ash pan 16, whilst in the other figures the ring 121 is secured to the blast tube 12. The source of power is a driven shaft 122, as indicated in the drawing.

45 What we claim is:—

1. A gas producer comprising a fixed shell, a blast tube below the shell, perforated arms on the tube, a hollow perforated ring on the arms, means for rotating the tube and means for supplying air to the tube.

50 2. A gas producer comprising a fixed shell, a blast tube below the shell, perforated arms on the tube, lugs on the upper surfaces of the arms, means for rotating the tube and means for supplying air to the tube.

55 3. A gas producer comprising a fixed shell, a blast tube below the shell, perforated arms on the tube, lugs on the upper surfaces of the arms, a hollow perforated ring on the ends of the arms, means for rotating the tube and means for supplying air to the tube.

60 4. A gas producer comprising a fixed

shell, a blast tube below the shell, perforated arms on the tube, a hollow perforated ring on the arms, an ash pan secured to the tube, means for rotating the tube and means for supplying air to the tube. 70

5. A gas producer comprising a fixed shell, a blast tube below the shell, perforated arms on the tube, lugs on the upper surfaces of the arms, an ash pan secured to the tube, means for rotating the tube and 75 means for supplying air to the tube.

6. A gas producer comprising a fixed shell, a blast tube below the shell, perforated arms on the tube, lugs on the upper surfaces of the arms, a hollow perforated ring on the 80 ends of the arms, an ash pan secured to the tube, means for rotating the tube and means for supplying air to the tube.

7. A gas producer comprising a fixed shell, a blast tube below the shell, perforated arms on the tube, a hollow perforated ring on the arms, an ash pan secured to the tube, a casing secured to the end of the shell, means for rotating the tube and means for 85 supplying air to the tube. 90

8. A gas producer comprising a fixed shell, a blast tube below the shell, perforated arms on the tube, lugs on the upper surfaces of the arms, an ash pan secured to the tube, a casing secured to the end of the shell, 95 means for rotating the tube and means for supplying air to the tube. 95

9. A gas producer comprising a fixed shell, a blast tube below the shell, perforated arms on the tube, lugs on the upper surfaces of the arms, a hollow perforated ring on the ends of the arms, an ash pan secured to the tube, a casing secured to the end of the shell, means for rotating the tube and means for 100 supplying air to the tube. 105

10. A gas producer comprising a fixed shell, a blast tube extending upwards into the shell, plough-shaped and perforated arms on the tube, lugs on the upper surfaces of the arms, a hollow perforated ring on the ends of the arms, means for rotating the tube and means for supplying air to the tube. 110

11. A gas producer comprising a fixed shell, a blast tube below the shell, plough-shaped and perforated arms on the tube, an ash pan secured to the tube, a casing secured to the end of the shell, means for rotating the tube and means for supplying air to the tube. 115

12. A gas producer comprising a water-jacketed shell, a blast tube below the shell, perforated arms on the tube, a spraying apparatus in the tube, a pipe leading from the water jacket to the spraying apparatus, 120 means for rotating the tube and means for supplying air to the tube.

13. A gas producer comprising a water-jacketed shell, a blast tube below the shell, perforated arms on the tube, lugs on the 125 130

upper surfaces of the arms, a hollow perforated ring on the ends of the arms, a spraying apparatus in the tube, a pipe leading from the water jacket to the spraying apparatus, means for rotating the tube and means for supplying air to the tube.

14. A gas producer comprising a shell, a blast tube below the shell, hollow arms on the tube, perforations in the arms, lugs on the upper surface located in advance of the perforations, means for rotating the tube and means for supplying air to the tube.

15. A gas producer comprising a shell, a

blast tube below the shell, hollow arms on the tube, a hollow perforated ring on the ends of the arms, perforations in the arms, lugs on the upper surface located in advance of the perforations, means for rotating the tube and means for supplying air to the tube.

In testimony that we claim the foregoing as our invention we have signed our names this 13th day of February, 1923.

GEORGE HERBERT BENTLEY.
EDMUND GARDNER APPLEBY.
